DESIGN FOR A PORTABLE SANCTUARY LAMP

Karl Rau, Medina, Ohio, assignor to The A. I.
Root Company, Medina, Ohio, a corporation of Ohio

Application August 3, 1940, Serial No. 94,172

Term of patent 14 years

To all whom it may concern:

Be it known that I, Karl Rau, a citizen of the United States, residing at Medina, in the county of Medina and State of Ohio, have invented a new, original, and ornamental Design for a Portable Sanctuary Lamp, of which the following is a specification, reference being had to the accompanying drawing, forming a part thereof.

Figure 1 is a front perspective of a portable sanctuary lamp showing my new design; and Figure 2 is a side perspective of the same taken at a right angle to Figure 1.

I claim:

The ornamental design for a portable sanctuary lamp, substantially as shown.

KARL RAU.
